UNITED STATES PATENT OFFICE.

LEONARD D. NILSON, OF WAYZATA, MINNESOTA, ASSIGNOR TO MARQUETTE MANUFACTURING COMPANY, OF ST. PAUL, MINNESOTA.

PRESS.

Application filed November 11, 1926. Serial No. 147,694.

The object of my invention is to provide a press particularly adapted for use in connection with garage automotive work and being simple and durable and comparatively inexpensive to manufacture.

More particularly it is my object to provide a press for garage work, such as straightening disk wheels, crank shafts, cam shafts and the like and for use in connection with replacing pins, keys and gears.

A further object is to provide my press of substantial construction with a press screw of sturdy construction adapted to have fittings for different kinds applied thereto for

garage work of different kinds.

Still a further object is to provide a work table which is readily and conveniently adjustable as to height for the different kinds of work encountered and readily adapted to receive fittings employed in the use of automotive repairs, the table being guidingly held in position by the press frame and locked in any of its adjusted positions by the use of latch mechanisms.

A further object is to provide suitable operating mechanism for actuating the press screw employing bevel gears operatively connected.

Still a further object is to provide reduction gear mechanism whereby the press screw may be operated selectively at either a high or low speed and to provide a convenient means which is readily accessible to the operator of the press for adjusting the operating mechanism for high or low speed operation.

Another object is to provide a handle for actuating the operating mechanism and a reversible ratcheting means for connecting the handle thereto.

With these and other objects in view, my invention consists in the construction, arrangement and combination of the various parts of my press, whereby the objects contemplated are attained, as hereinafter more fully set forth, pointed out in my claims, and illustrated in the accompanying drawings in which:

Figure 1 is a side elevation of my improved press showing some of the fittings for handling different classes of work in position thereon.

Figure 2 is an end elevation of the same.

Figure 3 is a vertical detail sectional view taken on the line 3—3 of Figure 2, the parts

being enlarged to better illustrate the construction of my device.

Figure 4 is a further enlarged detail sectional view on the line 4—4 of Figure 3 illustrating part of the mechanism for operating the press screw.

Figure 5 is a detail sectional view on the line 5—5 of Figure 3 illustrating part of the reduction gear mechanism.

Figure 6 is a detail sectional view taken on the line 6—6 of Figure 3 illustrating parts of the speed control.

Figure 7 is a detail sectional view taken on the line 7—7 of Figure 3.

Figure 8 is a detail sectional view taken on the line 8—8 of Figure 1 showing the application of fittings used with the press.

Figure 9 is a detail sectional view on the line 9—9 of Figure 3 illustrating part of the ratchet mechanism; and

Figure 10 is a detail sectional view on the line 10—10 of Figure 3.

My improved press includes a pair of vertical side members 10 which are of I-beam construction. The members 10 rest on a pair of angle members 12 forming the base of the device and are secured thereto by angle braces 14. The braces 14 are riveted to the members 10 and 12 for connecting them together.

To properly space the angle members 12 as well as the upright members 10 and to rigidly hold them in proper position for forming a rigid frame, I provide rods 16 extending through the angle members 12 and secured thereto by nuts 18. Between the angle members 12 and on the rods 16 are spacer tubes 20. The spacers 20 hold the base parts spaced apart and at the same time rigid. At the upper end of the side members 10 I mount a press head. The press head comprises a pair of spaced plates 22 riveted to the flanges of the I-beams or uprights 10. The members 10, 12, 20, and 22 form a rigid press frame. A press head A, a work table, and an operating mechanism are all supported upon the press frame.

Secured between the plates 22 by bolts 26 is the press head A. The press head as illustrated is a casting and has a sleeve like portion 28. A press screw 24 is slidably mounted within the sleeve 28 of the press head A and is held against rotation therein by pins 30 which are received in openings 32 formed in the press screw 24. The pins 30 slide vertically in slots 34 which are provided in the sleeve 28. A pin

36 is inserted through the upper end of the screw 24 and limits the downward movement thereof by engaging the upper end of the sleeve 28.

5 The press screw 24 is threaded as at 38 and a bevel gear 40 is internally screw threaded and coacts therewith and is mounted thereon. Between the bevel gear 40 and the sleeve 28 I position a thrust bearing element 42 to take 10 care of the tremendous upward thrust exerted on the press screw 24 when my device is in operation. The lower end of the press screw 24 is reduced as at 44 for receiving for instance a fitting 46. The fitting 46 is provided with a socket 48 projecting over the reduced portion 44 and is held thereon by a set screw 50. The set screw 50 coacts with a groove 52 in the press screw 24. The fitting 46 is V-shaped as at 54. Many 15 different kinds of fittings may be employed upon the lower end of the press screw 24.

I provide a work table B for my press comprising plates 56 positioned with their ends on each side of the side flanges of the upright members 10. Spacer castings 58 to which the plates 56 are riveted hold the plates spaced apart. The spacer castings 58 are positioned so that the two plates 56 project beyond them, thus forming guides for the work table. The 20 work table is guidingly held between and upon the uprights 10.

By this construction it is obvious that the work table is capable of sliding movement vertically on the upright members 10 of the 25 press frame.

For maintaining the work table at any desired elevation, on the uprights 10 I provide a series of substantially rectangular slots 60 in the members 10. Coacting selectively with 30 the slots 60 are latch mechanisms 62 each being pivoted on a pin 64 which in turn is supported by ears extending from the spacer casting 58 whereby the latch mechanism 62 is pivotally mounted. Each latch mechanism 45 62 is constrained in one direction by a spring 66 whereby a lug 68 thereon is maintained in engagement with one of the slots or openings 60. Each latch mechanism 62 is provided with an extension 63 adapted to frictionally 50 engage the web of an upright 10 to prevent sudden dropping of the work table when the latch is moved to the dotted line position shown in Figure 3. This construction adapts my improved press for various kinds of work 55 usually encountered about a garage in the repair of engines of all kinds, although my particular construction of press is best applicable for automotive work.

I provide fittings 70 and 72 for coacting 60 with the plates 56 of the table B. The fitting 70 is substantially a face plate provided with an opening 74. A pair of ribs 76 are provided on the underside of the fitting 70 to properly position the fitting on the plates 56 and prevent its accidental displacement therefrom,

The ribs 76 at the same time permit easy sliding movement of the fitting 70 on the table B at the will of the operator. The fitting 72 is provided with a V-notch 78 and a lug 80 extending downwardly between the plates 56 70 for positioning the fitting on the plates and allowing easy sliding movement of the fitting longitudinally relative to the table B. Preferably I provide two of the fittings 72.

Press screw actuating mechanism.

The mechanism whereby I rotate the bevel gear 40 for moving the press screw 24 through the sleeve 28 will now be described in detail.

Secured to the web of one of side members 10 is a bearing bracket 82. Rotatably mounted in the bracket 82 is a shaft 84. A downwardly extending portion 86 of the sleeve 28 is provided with an enlarged bearing 88. The bearing 88 rotatably receives a sleeve 90 formed integral with the bevel gear 92. The bevel gear 40 rests upon and is supported by the gear 92 and as a result thereof the press screw 24 is held in position within the press head A. 90 The sleeve 90 and bevel gear 92 are rotatably mounted on one end of the shaft 84. A head 94 is formed on the shaft 84 to prevent its longitudinal movement in one direction. The head 94 engages the bevel gear 92. Keyed as 95 at 96 on the outer end of the shaft 84 is a ratchet hub 98. The hub 98 is formed with ratchet teeth. Rotatably mounted on the ratchet hub 98 is an enlarged pawl carrying hub or fitting 100. A crank arm 102 is rotatably mounted relative to the shaft 84 by means of a shouldered cap screw 104. The crank arm 102 is snugly received in a groove 106 formed in the pawl carrying hub or fitting 100 and is further secured thereto by 100 means of a bolt 108. The bolt 108 extends through the crank arm and through a projection 105 110 formed on the hub 100.

From the description of the parts just described, it will be obvious that the hub 100 and crank arm 102 are free to rotate relative to the shaft 84 and the ratchet hub 98. The crank arm 102 is provided with a handle 112 whereby the arm 102 can be actuated by an operator of the press for rotating the shaft 115 110 115 120 125 130 135 140 145 150 155 160 165 170 175 180 The pawl 114 is provided with a beveled edge 128 whereby rotation of the handle in one direction will disengage the pawl successively from the notches 126 against the action 5 of the spring 124. For reversing the ratcheting action, it is merely necessary to turn the pawl 114 to an angle of 180 degrees whereby the beveled edge 128 engages the opposite sides of the notches 126. For accomplishing 10 this result and insuring against accidental rotation of the pawl 114, I provide a pin 130 in the spindle 118 for engaging an elongated notch 132 in the sleeve 116.

I will now describe the mechanism whereby 15 rotation is transmitted from the shaft 84 to the bevel gear 90 selectively at a high or low ratio of speed.

Keyed to the shaft 84 by means of a key 134 is an eccentric member 136. Mounted on 20 the shaft 84 is a disk 138 provided with notches 140 in its periphery. The disk 138 rotates in unison with the eccentric member 136 and consequently the shaft 84 by virtue of pins 141 extending through both the eccentric member 25 and the disk. Rotatably mounted on the eccentric member 136 is a gear wheel 142. The gear wheel 142 has an enlarged hub whereby a plurality of rollers 144 may be inserted between the hub and the eccentric member 136 to form a roller bearing 30 to reduce friction.

From the foregoing it will be obvious that rotation of the shaft 84 will cause the gear 142 to move eccentrically relative to the shaft 35 but it need not necessarily rotate therewith.

Rotatably mounted on the shaft 84 is a sleeve 146. The sleeve 146 is in operative connection with the sleeve 90 on the bevel gear 92 by the jaws 148. Integral with the sleeve 40 146 is a disk 150. Secured to the disk 150 as by rivets or the like 152 is an internal gear 154.

The gear 142 is provided with teeth 156 and the internal gear 154 is provided with teeth 158 45 meshing therewith. The number of teeth 158 exceeds the number of teeth 156 so that a differential gearing mechanism results when the eccentric member 136 is rotated.

In order to rotate the sleeve 146 at a reduced 50 speed relative to the shaft 84 it is necessary to prevent rotation of the gear 142. I accomplish this in the following manner.

Pivoted between ears 160 on the gear 142 is a bell crank lever 162. The bell crank lever 55 162 is spring actuated in one direction by a spring 164 for holding the lever 162 in the full line position as illustrated in Figure 3 and Figure 5. For holding the arm 162 in engagement with a roller 168 I provide a flange 170. The flange 170 is secured to a shaft 172 which is rotatably mounted in a bracket 174 secured to the web of the side member 10 above the bearing flange 82. The shaft 172 is 60 provided with an enlarged portion 176 on which the roller 168 is rotatably mounted. A

spool like member 178 is secured to the shaft 172 on the opposite side of the web from the bracket 174 and is adapted to be rotated and in turn rotate the flange 170 at the will of the operator. For preventing rotation of the 70 shaft 172 a pin 180 is slidably mounted in the flanges of the spool member 178 and is provided with an enlarged portion or shoulder 182. A spring 184 is interposed between the shoulder 182 and the outer flange of the spool 75 178 whereby the pin 180 is actuated to slide to position where the end 186 thereof may engage an opening 188 formed in the web of one of the side members 10. Another opening 191 is provided to receive the end 186 when the 80 spool member 178 is in another of its rotated positions relative to the position shown in Figures 3 and 6.

The flange 170 is provided with a cut-away portion 190 whereby the flange when rotated 85 to the dotted line position illustrated in Figure 5 will allow the spring 164 to release the lever 162 from the roller 168. When the lever 162 is free to be moved by the spring 164, the end 166 thereof engages the periphery of the 90 disk 138. When the disk has been rotated a sufficient distance relative to the gear 142, it brings the notches 140 to register with the end 166 of the lever 162. The spring 164 forces the end 166 to enter any of the 95 notches 140.

In the operation of my device the work table may be adjusted or moved vertically for changing the elevation suitable to the work being done. When moving the work table B 100 then the latches 62 are moved as for instance to the dotted line position illustrated in Figure 3. The lugs 68 disengage their respective notches 60 and permit free movement of the table B. The work table may be slid vertically relative to the side members 10 until the lugs 68 are opposite the notches nearest to the desired elevation of the work table. The latches 62 are then released and the springs 66 105 actuate them to coat with the notches 60. 110

When it is desired to quickly adjust the press screw 24 relative to the article to be worked on, then the spool 178 is rotated to the position where the end 186 of the pin 184 115 engages the notch 190. In this position the cut-away portion or notch 190 of the flange 170 is parallel with the arm 162 thereby allowing the arm to engage one of the notches 140 in the disk 138 as illustrated in the dotted line position in Figure 3. 120

When the parts of the gearing mechanism are in this position, rotation is transmitted from the shaft 84 through the disk 138, arm 162 and gear 142 to the gear 154 and the sleeve 146. In this position all of the parts just mentioned rotate in unison whereby one turn of the crank arm 102 rotates the bevel gear 92 one turn and advances the press screw the distance of one of the threads 38. When for instance the fitting 46 has engaged a piece of 130

work placed on the face plate 70 and it is desired to increase the operator's leverage, the shaft 84 is rotated until the arm 162 is in position to engage the roller 168 as shown in Figure 5. The lever 162 is then manually moved to the full line position and the disk 170 is rotated to the position shown in Figure 3.

The coaction of the lever 162 and the roller 10 168 prevents further rotation of the gear 142 and the flange 170 maintains the arm in engagement with the roller. When the parts are in this position and the shaft 84 is rotated, it causes the gear 142 to move eccentrically 15 relative to the shaft but the gear is not permitted to be rotated. Rotation of the eccentric member 136 causes the teeth 156 to successively mesh with the teeth 158 thereby advancing the internal gear 154 a distance of the 20 number of teeth there are in the gear 154 in excess of those on the gear 142. This causes a very slow rotation of the bevel gear 92 and a consequent powerful press action on the work 25 between the fittings 46 and 70.

In the operation of my device, the fitting 46 may be removed and the end 44 may be employed for forcing shafts from gears or the like which are placed on the face plate 70. The shafts in such cases extend through the 30 opening 74. When it is desired for instance to straighten a shaft or the like, the two fittings 72 are employed in conjunction with the fitting 46. The shaft is laid in the V-grooves 78 with the high point of the bend in the shaft 35 in the groove 54. A downward pressure of the press screw 24 tends to bend the shaft toward straightened position.

Having thus described my invention, it will 40 be obvious that I have provided a press particularly adaptable for use in garages and which may be used for a variety of other work as well.

I have also provided a suitable mechanism 45 for reducing the speed at which the screw is operated whereby a great leverage is obtained. My mechanism is so arranged whereby the 50 gearing-down mechanism may conveniently be rendered inoperative and the press operated at high speed as for instance when adjusting it to the work being done.

Some changes may be made in the details 55 of construction and arrangement of the various parts of my invention, without departing from the real spirit and purpose of my invention, and it is my intention to cover by my claims, any modified forms of structure or use of mechanical equivalents, which may be reasonably included within their scope.

I claim as my invention:

60 1. A press of the class described comprising a frame having spaced apart upright members provided with vertically spaced aligned openings, a work table vertically slidable on said upright members, a latch at each end of the 65 work table adapted to selectively coact with

said aligned openings in said upright members whereby the ends of the work table are supported on said upright members, said latches having portions adapted to frictionally engage the frame when they are in unlatched position. 70

2. A press of the class described comprising a frame having spaced apart upright members provided with vertically spaced aligned openings, a work table vertically slidable on 75 said upright members and guidingly held thereby, a spring actuated latch mechanism at each end of the work table, each latch comprising a pivoted member having portions extending in opposite directions beyond the pivot means, one of said portions being adapted to frictionally engage one of the upright members when the latch is in one position and the other portion having a hook thereon adapted to selectively coact with said aligned 80 openings in said upright member when the latch is in another position whereby the ends of the work table are supported on said upright members. 85

3. A press of the class described comprising 90 a base, a frame mounted thereon, a press head and a work table supported on said frame, said work table being capable of adjustment on said frame for varying the distance between said table and press head, a latch mechanism for holding said table in any of its adjusted positions, said latch mechanism including a portion adapted to frictionally engage the frame when in unlatched position, a press screw slidably mounted in said press head, a 95 bevel gear threaded on the screw below said press head for movement to said screw relative to said press head, a second bevel gear coacting with the first bevel gear for supporting the press screw in said press head. 100

4. A press of the class described comprising a base, a frame mounted thereon, a press head and a work table supported on said frame, a press screw slidably mounted in said press head, a bevel gear threaded on the screw below 110 said press head for causing movement of said screw relative to said press head and common means in connection with said gear for imparting rotation thereto and for supporting the press screw in said press head. 115

5. A press of the class described comprising a base, a frame mounted thereon, a press head and a work table supported on said frame, said work table being capable of adjustment on 120 said frame for varying the distance between said table and press head, a latch mechanism for holding said table in any of its adjusted positions, a press screw slidably mounted in said press head, a bevel gear mounted on the screw below the press head for moving it within the press head, a second bevel gear coacting with the first bevel gear for supporting the press screw in said press head, means for rotating the second bevel gear, said means comprising a crank and a reversible ratchet con- 125 130

means for rotating said eccentric member, a disk rotatable with the eccentric member and having notches in the periphery thereof, an arm on said gear normally in engagement with one of said notches and means for causing its disengagement therefrom.

13. A press of the class described comprising a base, a frame mounted thereon, a press head and a work table supported on said frame, said work table being capable of adjustment on said frame for varying the distance between said table and press head, a latch mechanism for holding said table in any of its adjusted positions, a press screw operatively supported by said press head, means coacting with said screw for operating it, said means comprising an internal gear, a gear mounted within said internal gear and in engagement therewith and having fewer teeth than said internal gear, an eccentric member, said gear being rotatable on said eccentric member for rotating said eccentric member, a disk rotatable with the eccentric member and having notches in the periphery thereof, an arm on said gear normally in engagement with one of said notches and means for causing its disengagement therefrom.

14. A press of the class described comprising a base, a frame mounted thereon, a press head and a work table supported on said frame, a press screw operatively supported by said press head, means coacting with said screw for operating it, said means comprising an internal gear, a gear mounted within said internal gear and in engagement therewith and having fewer teeth than the internal gear, an eccentric member, said gear being rotatable on said eccentric member, means for rotating the eccentric member, a disk rotatable with the eccentric member and having notches in the periphery thereof, an arm on said gear, a spring for normally causing said arm to move to notch engaging position and a projection on the frame for holding said arm against the action of the spring.

15. A press of the class described comprising a base, a frame mounted thereon, a press head and a work table supported on said frame, a press screw operatively supported by said press head, means coacting with said screw for operating it, said means comprising an internal gear, a gear mounted therein in engagement therewith and having fewer teeth than the internal gear, an eccentric member, said gear being rotatable on the eccentric member, means for rotating the eccentric member, a disk rotatable with the eccentric member and having notches in the periphery thereof, an arm on said gear, a spring for normally causing said arm to move to notch engaging position, a roller on the frame for engaging said arm when it is not in engagement with one of said notches and a movable latch adjacent said roller for holding said arm in engagement with the roller.

16. A press of the class described comprising a base, a frame mounted thereon, said frame having spaced apart upright members provided with vertically spaced aligned openings, a work table vertically slidably on said upright members and guidingly held thereby, a spring actuated latch mechanism at each end of the work table adapted to selectively coat with said aligned openings in said upright members whereby the ends of the work table are supported on said upright members, a press head supported on said frame, a press screw operatively supported by said press head, means coacting with said screw for operating it, said means comprising an internal gear, a gear mounted therein in engagement therewith and having fewer teeth than the internal gear, an eccentric member, said gear being rotatable on the eccentric member, means for rotating the eccentric member, a disk rotatable with the eccentric member and having notches in the periphery thereof, an arm on said gear, a spring for normally causing said arm to move to notch engaging position, a roller on the frame for engaging said arm when it is not in engagement with one of said notches and a movable latch adjacent said roller for holding said arm in engagement with the roller.

17. A press of the class described comprising a base, a frame mounted thereon, said frame having spaced apart upright members provided with vertically spaced aligned openings, a work table slidably mounted on said upright members, a spring actuated latch mechanism at each end of the work table adapted to selectively coat with said openings whereby the work table is supported, a press head on said upright members, a press screw slidably mounted in said press head, a crank for actuating said press screw, means for operatively connecting the crank to the screw comprising an eccentric member operable from the crank, a gear mounted on the eccentric member, an internal gear having said gear received therein and in mesh therewith, said internal gear having more teeth than said gear and means for preventing rotation of the gear.

18. A press of the class described comprising a base, a frame mounted thereon, said frame having spaced apart upright members provided with vertically spaced openings, a work table slidably mounted and guidingly held on said upright members, spring actuated latch mechanisms on said work table adapted to selectively coat with said openings whereby the work table is supported, a press head on said upright members, a press screw slidably mounted therein, a crank for actuating said press screw relative to said press head, means for operatively connecting the crank to the screw comprising an eccentric member operable from the crank, a gear mounted on the eccentric member, an inter-

nal gear having said gear received therein and in mesh therewith, a notched disk secured to said eccentric member, an arm pivoted on said gear and spring actuated toward position for engaging a notch in said disk and means for causing disengagement of the arm from the disk, said last means serving to engage the arm and prevent rotation of the gear.

19. A press of the class described comprising a base, a frame mounted thereon, said frame having spaced apart upright members provided with vertically spaced openings, a work table slidably mounted and guidingly held on said upright members, spring actuated latch mechanisms on said work table adapted to selectively coact with said openings whereby the work table is supported, a press head on said upright members, a press screw slidably mounted therein, a crank for actuating said press screw relative to said press head, means for operatively connecting the crank to the screw comprising a reversible ratchet mechanism and an eccentric member operable from the crank, a gear mounted on the eccentric member, an internal gear having said gear received therein and in mesh therewith, a notched disk secured to said eccentric member, an arm pivoted on said gear and spring actuated toward position for engaging a notch in said disk and means for causing disengagement of the arm from the disk, said last means serving to engage the arm and prevent rotation of the gear.

20. A device of the class described comprising a frame, a shaft rotatably mounted relative thereto, an eccentric member and a notched disk secured to said shaft, a gear mounted on said eccentric member, an internal gear encircling said gear and meshing therewith, the teeth of said gear and said internal gear being different in number, an arm on said gear resiliently constrained toward position to engage said notched disk, means on the frame for engaging said arm and thereby maintaining it disengaged from said notched disk and preventing rotation of the gear.

21. A device of the class described comprising a frame, a shaft rotatably mounted thereon, an eccentric member and a notched disk secured to said shaft, a gear mounted on said eccentric member, an internal gear encircling said gear and meshing therewith, the teeth of said gear and internal gear being different in number, an arm on said gear resiliently constrained toward position to engage said notched disk, and a roller on said frame in position to engage said arm when it is disengaged from said notched disk.

22. A device of the class described comprising a frame, a shaft rotatably mounted relative thereto, an eccentric member and a notched disk secured to said shaft, a gear mounted on said eccentric member, an internal gear encircling said gear and meshing therewith, the teeth of said gear and internal gear being different in number, an arm on said gear resiliently constrained toward position to engage said notched disk, a roller on said frame in position to engage said arm when it is disengaged from said notched disk, a flange for engaging said arm and thereby maintaining it disengaged from the notched disk and engaged with the roller, a portion of said flange being cut away whereby rotation of the flange to a predetermined position will allow the arm to be disengaged from the flange and the roller.

23. A device of the class described comprising a frame, a shaft rotatably mounted relative thereto, an eccentric member, a gear mounted on said eccentric member, an internal gear encircling said gear and meshing therewith, the teeth of said gear and internal gear being different in number, an arm on said gear resiliently constrained toward position to engage a portion of the eccentric member, a roller on said frame in position to engage said arm when it is disengaged from said shaft, and a projection adjacent the roller for engaging the arm and thereby maintaining its engagement with said roller.

Des Moines, Iowa, November 4, 1926.

LEONARD D. NILSON.
